UNITED STATES PATENT OFFICE.

SAMUEL W. REYNOLDS, OF TOLEDO, OHIO.

DESIGN FOR A SNAP-HOOK BODY.

44,288.

Specification for Design.

Patented July 1, 1913.

Application filed September 28, 1910. Serial No. 584,380. Term of patent 14 years.

To all whom it may concern:

Be it known that I, SAMUEL W. REYNOLDS, a citizen of the United States, residing at Toledo, county of Lucas, State of Ohio, have invented a new, original, and ornamental Design for Snap-Hook Bodies, of which the following is a specification, reference being had to the accompanying drawing, forming part thereof.

The figure is a perspective view showing the design embodying my invention.

I claim:

The ornamental design for a snap hook body, as shown.

SAMUEL W. REYNOLDS.

Witnesses:

LULU G. FOX,
ELIZABETH A. MURPHY.
